UNITED STATES PATENT OFFICE.

WILLIAM E. WAGNER, OF GORDON, PENNSYLVANIA.

DESIGN FOR A CHRISTMAS-TREE ORNAMENT.

SPECIFICATION forming part of Design No. 24,726, dated October 1, 1895.

Application filed August 7, 1895. Serial No. 558,551. Term of patent 14 years.

To all whom it may concern:

Be it known that I, WILLIAM E. WAGNER, of Gordon, in the county of Schuylkill and State of Pennsylvania, have invented and produced a new and original Design for an Ornament for Christmas-Trees and the Like, of which the following is a full, clear, and exact description.

Reference is to be had to the accompanying drawing, forming a part of this specification, in which the figure represents a side elevation of an ornament embodying my new design.

The leading feature of my design consists in the suspended ornamental body within a tufted frame. 15

I claim--

The design for an ornament for Christmas trees and the like, herein shown and described.

WILLIAM E. WAGNER.
